UNITED STATES PATENT OFFICE.

RICHARD G. PARANTAU, OF LOS ANGELES, CALIFORNIA.

MOP.

1,237,087.

Specification of Letters Patent.

Patented Aug. 14, 1917.

Application filed November 15, 1916. Serial No. 131,598.

To all whom it may concern:

Be it known that I, RICHARD G. PARANTAU, a citizen of the United States, residing at Los Angeles, in the county of Los Angeles and State of California, have invented new and useful Improvements in Mops, of which the following is a specification.

My invention relates to a mop.

10 It is an object of my invention to provide a mop securing means adapted to be mounted upon a mop stick in a manner that will insure its fixed position therein without the use of screws or other fastenings.

15 An objectionable feature in most mop mountings is that the latter become loose after the mop stick has been in use for some time, and that the stick is liable to rotate within the mounting.

20 It is another object of my invention to eliminate such a defect so that the mop mounting will under all conditions remain securely fixed in its original position on the mop stick.

25 Another object of this invention is to provide a wiper clamp bar which is locked in position by means of a pair of lock springs or detents whereby said bar may be instantly removed or adjusted in position.

30 With the above and other objects in view which will appear as the description proceeds, my invention consists in the construction and arrangement of parts hereinafter described and claimed.

35 In the accompanying drawings which form a part of this specification, I have illustrated a convenient and practical embodiment of my invention and in which:

Figure 1 is a perspective view of a complete mop provided with my mop mounting, and a portion of the handle broken away.

Fig. 2 is a view in vertical section taken longitudinally through the mop mounting and a portion of the mop stick.

45 Fig. 3 is a plan view from the bottom of Fig. 2.

Fig. 4 is a perspective view of the wiper clamping bar.

10 designates a cylindrical mop stick 50 whose end 11 is enlarged, there being an intermediate tapered shoulder 11'. One side of the end is cut away as at 12, for a purpose presently to be described. A sleeve 13 with a tapered end, and made preferably of 55 malleable iron, fits over the end of the mop stick. The sleeve 13 is flattened as at 14 to

correspond to the flattened end of the stick, which is inserted from the lower end of the sleeve and driven home so that the flattened end 12 of the stick will seat against the 60 flattened end 14 of the sleeve. This construction of the mounting of the mop stick in the sleeve prevents the rotation of the stick and insures a permanent attachment between the two, not liable to come apart 65 during the operation of the mop.

The outer end of the sleeve 13 has formed therewith a cross head 15 which is provided with upturned ends 16. A pair of reinforcing or bracing members 17 connect the 70 ends 16 with the inner end of the sleeve 13, said ends 16 and members 17 being preferably made of one piece with the sleeve and the cross head. The upturned ends 16 of the cross head are provided with cylindrical 75 sockets 18 adapted for the reception of the locking arms 19 of a cylindrical wiper clamping bar 20. The under face of the cross head 15 is provided with a longitudinal semi-cylindrical groove 21 adapted to coact 80 with the clamping bar 20. The outer end of the stick may be provided with a similar groove 21' in alinement with groove 21. The locking arms 18 of the clamping bar are provided on their inner sides with a series 85 of tooth-shaped recesses 22, the lower face of said recesses slanting inwardly and downward. These recesses coöperate with locking members or pawls 23 which are in the form of spring wire fastened to the upper 90 end of the sleeve at 24. Said locking members are L-shaped passing from the point 24 adjacent to the sides of the sleeve 13, then horizontally outward through bores 25 on the inner faces of the upturned ends 16. 95 The outer end of the locking members is pointed as at 26 to fit into the locking recesses 22.

From the foregoing description, the operation of the improved mop will be easily 100 understood. After the sleeve with its cross head has been mounted on the end of the mop stick as described, the wiper 27 is placed over the clamping bar 20 and the locking arms of said clamp are inserted in 105 the sockets 18 and pushed home. The points 26 of the locking members 23 will slide along the lower inclined faces of the recesses 22 and allow the clamping member to be moved toward the cross head as desired. When it is desired to remove the wiper, the hand is placed about the sleeve 13,

encircling the locking members 23, and the latter are pressed toward the sleeve, thereby withdrawing the points in engagement with the locking recesses of the locking arms, and 5 allowing the removal of the clamp with its wiper. It should be noted that the locking members allow the movement of the clamping bar in a wiper clamping direction, but lock said bar when the same is moved in a 10 wiper releasing direction.

I claim:

1. In a mop, a handle, a cross head mounted thereon, said cross head having a vertical socket at each end, a clamping bar having 15 upturned locking arms adapted to engage said sockets, said arms being provided on their inner faces with tooth-shaped pawl engaging recesses, and a pair of L-shaped spring wire pawls having pointed ends 20 adapted to engage said recesses for locking said clamp in position, said pawls having their upper portions extending longitudinally of the lower end of said handle, and being adapted to be encircled by the hand 25 and pressed toward the handle, whereby the

pointed ends of said pawls are withdrawn from said recesses to allow the removal of the clamping bar.

2. In a mop, a handle, a sleeve in which said handle is mounted, a cross head mounted on the lower end of said sleeve, said cross head having clamping bar receiving apertures at the ends, a clamping bar having upturned ends adapted to engage said apertures, the ends of said clamping bar having means for 30 engaging a pair of spring pawls, a pair of spring pawls co-acting with said means to lock said clamping bar against movement in a clamp releasing direction, said spring pawls being mounted on the upper end of 35 said sleeve and extending longitudinally thereof; so that they may be encircled by the hand and pressed against said sleeve to withdraw said pawls and allow movement of said clamping bar in a bar releasing 40 direction.

In testimony whereof I have signed my name to this specification.

RICHARD G. PARANTAU.
